UNITED STATES PATENT OFFICE.

JULIUS G. BREITENSTEIN, OF CHICAGO, ILLINOIS.

BUTTON.

SPECIFICATION forming part of Letters Patent No. 769,053, dated August 30, 1904.

Application filed November 16, 1903. Serial No. 181,301. (No model.)

To all whom it may concern:

Be it known that I, JULIUS G. BREITENSTEIN, a citizen of the United States, residing at Chicago, in the county of Cook and State of Illinois, have invented new and useful Improvements in Buttons, of which the following is a specification, reference being had to the accompanying drawings, forming a part thereof.

This invention relates to buttons which are made with cloth face protected by a rim of hard rubber or other hard substance and which are provided with a tuft for sewing them to the garment.

It consists in the features of construction set out in the claims.

In the drawings, Figure 1 is an axial section of my improved button, certain of the elements being shown exaggerated in thickness in order to make the construction apparent. Fig. 2 is a bottom or under side plan view of the same. Fig. 3 is a plan view of a retaining-wire. Fig. 4 is a view of the same part shown in Fig. 3 looking in the direction of the arrow 4 on said Fig. 3. Fig. 5 is a view similar to Fig. 2, showing a modified form of the retaining-wire. Fig. 6 is a section at the line 6 6 on Fig. 5.

This button comprises the shell A and collet B, clenched together in the customary manner and gripping between their flanges the face-cloth C, which covers the shell A, and inclosing between them the filling D for gripping and holding the tuft-cloth E, which protrudes through the central aperture of the collet B to form the protruding tuft e. All the parts thus described, assembled and clinched into a rigid unitary structure, are lodged in and protected by the hard marginal element of rim-piece F, said rim-piece having in its upper face a cavity for lodging the body of the button, with the face-cloth C exposed within the marginal flange F' of said rim-piece and with the tuft exposed through the central aperture of said rim-piece. The feature of my present invention consists of means for securing the remainder of the button to the part F. Said means I have shown in two forms. In the form shown in Figs. 1, 2, 3, and 4 it is a partial ring G, of wire, having 50 the curved portion, which constitutes a half-

circle, more or less, turned inward and upward and then outward at the ends, as seen in Figs. 3 and 4. This retaining device G is engaged with the collet B by pressing its ends together to close it up for entering both the 55 ends at once through the central aperture of the collet, whereupon, being released, the retainer G spreads out within the collet to the flange thereof, while the projecting points G' G' of the wire overhang the inner margin of 60 the collet at the outer side. After lodging the retainer in the collet, as described, the remaining elements of the body of the button are assembled in the usual order—to wit, first the tuft of cloth B, next the filling D, and finally the 65 shell A and face-cloth C, which are clenched to the collet in the usual manner—and said retainer G is thus securely held with only the projections G' G' protruding exposed. The rim-piece F is chambered or bored in from both 70 sides, leaving a diaphragm F², through which the central aperture F²⁰ is formed for the tuft e. The body of the button is lodged in the cavity at one side of the diaphragm, and said diaphragm is cut through at two diametrically 75 opposite points, forming notches F¹¹ F¹¹, and at the under face the diaphragm has the slopes F¹² F¹², extending each ninety degrees about the tuft-aperture from the notches F¹¹ F¹¹, respectively, to notches F¹³ F¹³, cut only part-way 80 through the diaphragm. The button-body, comprising parts assembled and clenched together as described, having the retainer G, with its projecting points G' G', exposed, is lodged in the rim-piece, said retaining-points 85 being passed through the notches F¹¹, and by a ninety-degree turn, in which the projections G' climb the slopes F¹² F¹², they are brought to the notches F¹³, in which they become engaged by reaction of the elastic retainer G, 90 thus securing the rim-piece to the remainder of the button.

Instead of employing the retainer G of the form shown, I sometimes use a simple straight pin H thrust through the tuft e after the 95 body of the button—that is, the button exclusive of the rim-piece—is constructed, the ends of said pin projecting in the same manner as the ends of the retainer G and being entered through the notches F¹¹ and engaged 100

by rotation with the notches F^{13} in the same manner as the other form. In this form the tuft by its elasticity serves to retract the ends of the pin into the notches F^{13} as the projections G' are retracted by the elastic reaction of the entire element G in the other form.

I claim—

1. A button comprising a body consisting of shell and collet with a cloth face clenched between the shell and collet; a securing device protruding from the collet, and projections at opposite sides of the securing device; a rim-piece or guard recessed at one side to receive the body, and apertured at the center to admit the securing element of the body, having notches extending from the central aperture which admits said projections, recesses in the margin about said aperture at the rear side to lodge said projections, and inclines leading from the notches to the recesses respectively.
2. A button comprising a body consisting of a shell and collet and the face-covering clenched between them; a tuft-cloth lodged in the collet and protruding therefrom at the center; the retaining device, G , lodged in the collet and having terminals projecting through the central aperture at opposite sides of the tuft and extending outwardly therefrom, the

rim-piece or guard recessed at the forward side to accommodate the body, and apertured at the center to accommodate the tuft having notches at opposite sides of the central aperture and recesses in the rear face extending from the margin of the central aperture, the projections of the retainer being adapted to enter through the notches and become engaged with the recesses by relative rotation of the body and rim-piece.

3. A button comprising a body and a rim-piece, the body having central means for securing the button and projections at opposite sides of said central means, the rim-piece having a central aperture and lateral notches therefrom through which the securing device and the lateral projections protrude, and having at the rear face recesses with which the lateral projections become engaged upon relative rotation of the body and rim-piece.

In testimony whereof I have hereunto set my hand, in the presence of two witnesses, at Chicago, Illinois, this 14th day of November, 1903.

JULIUS G. BREITENSTEIN.

In presence of—

CHAS. S. BURTON,
M. GERTRUDE ADY.
